UNITED STATES PATENT OFFICE

HARRY LAWSON PERRY, OF JAMAICA, NEW YORK

MULTIPLE PICTURE AMUSEMENT DEVICE

Application filed August 8, 1930. Serial No. 473,840.

The object of the invention is to provide a puzzle or amusement device comprising movable parts, each containing representations of parts of different complete pictures, which 5 may be adjusted to different relative positions to form said pictures.

In the drawing, which show a preferred embodiment of my invention:—

Fig. 1 is a plan view of the device.

10 Fig. 2 is a cross section through the line 2—2 of Fig. 1.

Fig. 3 is a plan view of the holding board with some of the strips in place.

15 Figs. 4 and 5 are sections on the lines 4 and 5 respectively of Fig. 3.

Fig. 6 is a plan view of one of the strips.

A holding board *a*, which may be formed of thick cardboard, is constructed to hold a series of longitudinally slidable flat strips, or 20 ribbons, 1, 2, 3, 4, arranged in parallelism, with the edges of adjacent strips contiguous, and a similar series of strips 5, 6, 7, 8, extending 25 at right angles to the strips 1, 2, 3, 4. The strips interweave in the manner of a one-and-one fabric weave; or (which is perhaps a better analogy) similarly to a basket weave. For example, strip 1 extends successively over strip 5, under strip 6, over strip 7 and under strip 8; while the next 30 strip 2 extends successively under strip 5, over strip 6, under strip 7 and over strip 8. There may be any desired number of strips in a series.

Each strip contains a number of "picture squares", each of which extends laterally 35 across the strip and along the strip for a distance equal to the width of the strip. Certain picture squares of each strip are adapted to "mate" respectively with other picture squares of the other strips to form a single complete picture. By sliding the strips longitudinally, the different picture squares which form units of a single complete picture may be correctly positioned. The solution 40 of the problem of producing a complete picture on the field of exposed squares is somewhat difficult, since the number of relative positions which the various strips may assume is almost infinite, and requires the exercise of 45 some intelligence and considerable patience,

besides affording profitable amusement to children and not inconsiderable relaxation to adults.

If the picture field contains sixteen squares, as in the embodiment illustrated, two picture 55 squares of a single strip, spaced apart a distance equal to the length of one picture square, will constitute units of the same complete picture. Two other picture squares, similarly spaced apart, will constitute units 60 of another complete picture. Almost the entire length of a strip may, therefore, be provided with contiguous picture squares, two contiguous squares being units of different pictures. In Fig. 6, A, A, indicate units 65 squares of one picture; B, B, unit squares of another picture; D, D, unit squares of a third picture; and E, E, unit squares of a fourth picture.

The number of complete pictures which 70 may be formed is only limited by the length of the strips.

It is possible, also, by the exercise of some ingenuity, to provide for the production of a complete picture composed of units of 75 which one unit, or each of two or more units, constitute also a unit of another picture or two or more other pictures. This arrangement is feasible particularly where the pictures are of similar character, as, for example, 80 pictures of human heads, each comprising units which may register with other units of other human heads. Such an arrangement permits of a great and almost endless variety of group combinations without the use 85 of impractically long strips.

Different expedients may be adopted to hold the strips in slidable relation to the holder and to permit each of the strips to be 90 readily manipulated in opposite directions. In the embodiment shown, the holding board *a* is provided, beyond opposite sides of the picture field, with slots through which strips extend so as to permit them to slide along the face and back of the holding board. I 95 prefer to provide, for each strip, a slot *b*, beyond one edge of the picture field and three slots *c*, *d* and *e*, beyond the other end of the picture field. Each strip extends over board *a*, through a slot *d*, under board *a*, through 100

a slot *c*, over the picture field, interweaving with other strips as described, through a slot *b*, and back under board *a*, through a slot *e* and over board *a*. The two ends of the strip thus extend beyond the same side of the strip; one end over the other. By grasping and pulling one or the other end of the strip, the strip may be pulled in one or the other direction.

- 10 In constructing the complete device, I prefer to mount the holding board *a* on a base-board *h*, securing the boards together at the corners, and permissively near two of the edges, by glue or mechanically, so as to leave 15 the middle areas free, one from another, to allow the thin strips to slide freely between them. Over the holding board *a* is mounted an under-frame *f* which has a central square opening enclosing, and of the exact size of, 20 the picture field. Upon the frame *f* is mounted an over-frame *g*, which is provided with a similar square central opening, preferably of greater dimensions than the opening in frame *f* and which leaves exposed the 25 edges of frame *f* surrounding the picture field. The frame *f* is preferably deeply cut away from the edges thereof beyond which the free ends of the strips project, to provide an appreciable space between the holding 30 board *a* and the over-frame, thereby facilitating the free sliding of the strips.

The extremities of the strip are preferably reinforced by means of a lateral bar *i*, or otherwise thickened, to prevent them being 35 pulled inwardly beyond the adjacent edges of the framework.

The strips may be formed of any suitable flexible material, such as tracing linen or other strong paper or fabric.

- 40 While the strips have been described as containing "picture units", it should be understood that I mean to comprise by such expression any units, whether pictorial or not, which, when associated with other units, 45 combine to form a composite unit. For example, the units may comprise letters which are adapted to be grouped into words, or words which are adapted to be grouped into sentences, or lines which are adapted to be 50 grouped into diagrams, or sectional maps which are adapted to be grouped into maps of large areas, etc.

While it is preferred to make the units perfectly square, this is not essential, since they 55 may be of other shapes, for example, oblong; and any number of (preferably) rectangular units may constitute a complete picture field.

What I claim and desire to protect by 60 Letters Patent is:

1. An amusement device comprising two series of independent strips, the strips of each series being in parallel relation, the strips of one series extending at an angle to the 65 strips of the other series and being inter-

woven therewith by extending alternately thereover and thereunder, each strip being provided with areas containing picture units adapted, when grouped with other picture units of other strips of the same series and with picture units of strips of the other series, to form different complete pictures, said strips being longitudinally movable independently of each other to visually expose different combinations of picture units. 75

2. An amusement device comprising a framework enclosing a picture field, two series of independent strips, the strips of one series extending alternately over and under, and at right angles to, the strips of the other series throughout said picture field, so as to visually expose thereon alternate rectangular areas of each strip, each strip extending from beyond one edge of the framework through the picture field and thence back under the picture field and beyond said edge, each strip being thus manually longitudinally slidable in either direction independently of the others, each of said strips containing on said rectangular areas picture units adapted to form parts of different pictures, and different strips containing picture units adapted to form parts of the same picture, whereby different pictures may be formed on the picture field by the longitudinal movement and adjustment of the strips of the two series. 80 85 90 95

In testimony of which invention, I have hereunto set my hand, at New York city, N. Y., on this 6th day of August, 1930.

HARRY LAWSON PERRY.
